CLAIM

The ornamental design for partially transparent IC card, as shown and described.

DESCRIPTION

FIG. 1 is an enlarged top, front and right side perspective view of a partially transparent IC card showing our new design;

FIG. 2 is a top plan view thereof;

FIG. 3 is a front elevational view thereof;

FIG. 4 is a rear elevational view thereof;

FIG. 5 is right side elevational view thereof;

FIG. 6 is a left side elevational view thereof;

FIG. 7 is a bottom plan view thereof; and,

FIG. 8 is a greatly enlarged cross-sectional view thereof, taken along line 8—8 in FIG. 2.

The broken line drawing in FIGS. 1, 2 and 8 is for illustrative purposes only and forms no part of the claimed design.
